UNITED STATES PATENT OFFICE.

ALFRED M. LANE, OF ST. LOUIS, MISSOURI, ASSIGNOR TO MONARCH METAL WEATHER STRIP COMPANY, OF ST. LOUIS, MISSOURI, A CORPORATION OF MISSOURI.

METAL WEATHER-STRIP.

1,219,009.

Specification of Letters Patent. Patented Mar. 13, 1917.

Application filed August 26, 1912, Serial No. 716,974. Renewed February 19, 1916. Serial No. 79,469.

To all whom it may concern:

Be it known that I, ALFRED M. LANE, a citizen of the United States, and a resident of the city of St. Louis and State of Missouri, have invented a new and useful Improvement in Metal Weather-Strips, of which the following is a specification.

The invention relates to weather strips and more particularly to those made of metal and applied to wooden frames and sashes. It has for its principal objects to prevent binding and insure an easy movement of the sash when it swells and shrinks, due to climatic changes; and to attain certain other advantages hereinafter more fully appearing.

The invention consists in the novel construction, arrangement and application of a flexible or resilient strip in conjunction with a coöoperating relatively rigid strip, and in the parts and arrangements and combinations of parts hereinafter described and claimed.

In the accompanying drawing which forms part of this specification and wherein like symbols refer to like parts wherever they occur,

Figure 1 is a fragmentary horizontal section through one side of a window casing and adjacent portion of a sash, showing a practical adaptation of the invention;

Fig. 2 is a fragmentary perspective view showing the rigid groove strip detached; and

Fig. 3 is a similar view of the resilient rib strip.

In the drawings, a portion of an ordinary window frame 1 is shown as arranged for a sliding sash 2. The inner vertical corner portion of the sash adjacent to the parting strip 3 is rabbeted, as at 4, to make room for the beaded groove portion 5 of a rigid metal weather strip member 6. This strip or member 6 has its beaded groove portion offset inwardly, as at 7, from its marginal portion 8 which is tacked or otherwise fastened to the sash. The sash is preferably rabbeted slightly also adjacent to said first mentioned rabbeted portion, so that the secured portion 50 of the strip lies flush with the face of the sash.

The coöoperating weather strip member 9 is relatively flexible and preferably resilient. It is secured along one marginal portion to

the window frame, as at 10, preferably under the stop member or molding 11. This flexible or resilient strip 9 is bent substantially at right angles adjacent to its opposite margin, as at 12, and then rebent or looped, as at 13, to provide a substantially undercut rib adapted to slide in the groove portion 5 of the rigid strip 6. The strip 9 is then rebent back against the portion 12 and extended beyond the body portion, as at 14, to provide a flange. This flange portion 14 works loosely in a groove 15 provided in the window frame.

In practice, the resilient strip is preferably made perfectly flat from the bent portion 12 to the margin of the portion which is secured to the window frame, so that it will lie normally against the face of the frame inside the groove or slideway for the sash; and the groove 15 is made wide enough to permit considerable movement of the strip away from the window frame without binding the flange portion 14 of the strip. By this arrangement the strip, owing to its resiliency, tends to hug close to the window frame, yet the sash may be fitted to its groove or slideway with considerable looseness, and will not rattle.

When the sash is hung with the groove strip and rib strip in engagement, as shown in Fig. 1, the body portion of the rib strip between the rib and its secured marginal portion is sprung normally away from the window frame; and should the sash shrink, the strip will yield still farther away from the frame. On the other hand, should the sash swell, the strip will move back in the direction of the window frame.

The coöoperating ribbed and grooved portions of the two strips are effective in preventing drafts and keeping out dust and grit; while no draft is permitted under the resilient strip, as it is fastened all along its margin; and practically no dust or grit can find its way around the flange portion 14 which works in the groove 15. It is noted that the grooved portion 5 of the comparatively rigid strip 6 and the rib portion of the relatively flexible strip 9 are, in effect, edge portions of the metal strips formed into U-shape, and that the U-shape portion which constitutes the rib is smaller than the other U-shape portion that constitutes the groove, and that the two U-shape portions

stand out at right angles to the adjacent portions of their respective strips. It is further noted that the outer surface of the rib is convex and that the inner surface of the 5 groove is concave and that the contact between the two surfaces is limited to the base portion. In consequence of the construction above described, the rib portion and the groove portion are capable of having a rocking 10 movement on each other while remaining in contact.

Obviously, the structure admits of considerable modification without departing from the invention. Therefore, I do not 15 wish to be limited to that shown.

What I claim is:

1. In a weather guard, the combination with a frame and a sash slidably mounted therein, of a relatively rigid metal strip 20 and a relatively flexible metal strip, one of said strips being secured to the frame and the other to the sash, said strips having co-operating portions engaged near one side of the slideway so as to prevent a draft between them, said engagement being such that the strips are capable of sliding longitudinally but are interlocked against independent lateral movement with respect to each other, said flexible strip being fastened 25 along one of its margins near the opposite side of the slideway, its body portion lying loose between the end face of the sash and adjacent face of the frame.

2. In a weather guard, the combination 30 with a frame and a sash slidably mounted therein, of a relatively rigid metal strip and a relatively flexible metal strip, one of said strips being secured to the frame and the other to the sash, said strips having co-operating portions engaged so as to prevent 35 a draft between them, said engagement being such that the strips are capable of sliding longitudinally but are interlocked against independent lateral movement with respect to each other, said flexible strip being fastened 40 along one of its margins, its body portion lying loose between the end face of the sash and adjacent face of the frame, and said flexible strip having its free 45 marginal portion flanged and working loosely in a slot provided therefor in the part on which it is mounted.

3. In a weather guard, the combination 50 with a frame and a sash slidably mounted therein, of a relatively flexible metal strip secured along one of its margins to the frame near one side of the slideway, the body portion of said strip lying loose between the end face of the sash and adjacent 55 face of the slideway and extending near the opposite side of the slideway, said strip having a longitudinally slideable but laterally interlocked weathertight engagement near its free margin with the sash.

4. In a weather guard, the combination

with a frame and a sash slidably mounted therein, of a relatively rigid metal strip secured to the sash, and a relatively flexible metal strip secured along one marginal portion to the frame adjacent to one side of the slideway for the sash, its body portion lying loose between the end face of the sash and adjacent face of the slideway, and its opposite marginal portion being flanged and working loosely in a slot provided therefor in the frame adjacent to the opposite side of said slideway, said metal strips having longitudinal portions engaged so as to prevent a draft between them, the engagement being such that the strips are capable of 75 sliding longitudinally but are interlocked against independent lateral movement with respect to each other.

5. In a weather guard, the combination with a frame and sash slidably mounted 80 therein, of a relatively rigid metal strip and a relatively flexible metal strip, one of said strips being secured to the frame and the other to the sash, said strips having co-operating portions engaged near one side of the slideway so as to prevent a draft between them, said engagement being such that the strips are capable of sliding longitudinally but are interlocked with each other independently of the part upon which 85 each strip is mounted against separation by movement of the sash in its plane in either direction, said flexible strip being fastened along one of its margins near the opposite side of the slideway, its body portion lying 90 loose between the end face of the sash and adjacent face of the frame.

6. The combination with a window frame and a window sash of a metal weather strip comprising two metal members mounted 105 vertically on the frame and on the sash respectively, the frame member being a wide flexible strip located between the side of the frame and the side edge of the sash and having a free marginal flange portion projecting toward said sash and contacting with the sash strip to form a floating metal joint, the flexibility of said frame member enabling its free marginal portion to accommodate itself to any horizontal movements 110 of the sash member without separating therefrom.

7. In a weather guard, the combination with a window frame having vertical slide-ways and a sash slidably mounted in said slide-ways and having grooves in its vertical end faces near one edge of the adjacent slide-way, of a metal weather strip for each slide-way, each weather strip comprising 120 two members constituting a sliding floating joint adapted to accommodate slight transverse and tilting movement of the sash relative to the frame, one of which members has a grooved offset portion located in the groove of the sash and the other member 125

having an offset portion engaging such grooved portion, said members being mounted on the frame and on the sash respectively, one of said members being a relatively rigid strip and the other being a relatively flexible strip, said flexible strip being located flatwise between the frame and the end face of the sash and being secured near the edge of the slideway farthest from the floating joint.

8. The combination, with a window frame and a window sash having grooves in its side edges, of metal weather strips, said weather strips comprising a metal member mounted on the sash and having a trough-shaped portion fixedly located in said groove, and a second metal member positioned in the runway of the frame between said sash and frame, and comprising a wide flexible strip secured to the frame along one side margin and having its free marginal portion provided with an offset rounded portion which enters said groove and contacts with said trough-shaped portion, the flexibility of said frame member permitting continuous contact between said members irrespective of the relative movement of the sash with respect to the frame, there being side clearance between said trough-shaped portion and said rounded portion whereby limited relative movement of the sash and

frame horizontally as well as angularly does not cause binding of said members.

9. The combination with a window frame and a sliding window sash of a metal weather strip comprising two metal members mounted on the frame and on the sash respectively, the sash member being rigidly attached to the edge of the sash to move therewith, and the frame member being a wide flexible strip arranged lengthwise of the slide-way and located between the side of the frame and the side edge of the sash and secured to the frame along one edge, the other edge of said frame member being free of said frame and having a marginal flange portion projecting toward said sash and contacting with the sash member to form a floating metal joint, the flexibility of said frame member enabling its free marginal portion to accommodate itself to any horizontal movements of the sash member without separating therefrom, whereby said members may slide freely on each other in all positions of said sash relatively to said frame.

St. Louis, Mo., Aug. 23, 1912.
